Primary Examiner — Kelley Donnelly(74) *Attorney, Agent, or Firm* — Notaro, Michalos & Zaccaria P.C.(57) **CLAIM**

The ornamental design for a tray, as shown and described.

DESCRIPTION

FIG. 1 is a front, left, top perspective view of a tray showing my design therefor;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged cross sectional view of FIG. 6, taken along line 8-8 thereof.

Throughout the drawings, broken lines show environment only and form no part of the claimed design.

1 Claim, 6 Drawing Sheets(56)
